HANGER BRACKET DEVICE

William J. Miller, Inglewood, Calif.

Application February 17, 1944, Serial No. 522,776

2 Claims. (Cl. 166—16)

1

This invention relates to a hanger bracket device, and it is primarily an object of the invention to provide a device of this kind designed to be attached to a well casing or tubing head for the purpose of holding in suspension such equipment as oil savers or the like so that such equipment can be readily applied to or removed from the tubing when joints are disconnected to remove a line from a well bore.

Another object of the invention is to provide a device of this kind which operates in a manner to eliminate the lifting of an oil saver or other equipment from a derrick floor to apply or remove the same.

The invention also has for an object to provide a device of this kind constructed in a manner to compensate for variable distances from the center of a well bore to center of post, as when an oil saver or the like is applied to the tubing or line, the tubing or line section when unscrewed will rotate in a wobbling manner or as an eccentric, as the connection or mounting for the device will eliminate the strain that may be imposed upon a saver or kindred equipment and thereby protect the sealing rings from considerable wear.

A still further object of the invention is to provide a device of this kind which is so mounted upon a well casing to allow an oil saver or other equipment to be swung away from the tubing or line when desired to permit workmen to readily use tongs to pull or raise the tubing or line and to facilitate the moving of the device into and out of the way position when not in use.

The invention consists in the details of construction and in the combination and arrangement of the several parts of my improved hanger bracket device whereby certain important advantages are attained, as will be hereinafter more fully set forth.

In order that my invention may be better understood, I will now proceed to describe the same with reference to the accompanying drawings, wherein:

Figure 1 is a view in elevation illustrating a hanger bracket device constructed in accordance with an embodiment of my invention and in applied position;

Figure 2 is a view in elevation of the assembly as illustrated in Figure 1 but at a one-quarter turn;

Figure 3 is a view in top plan of the invention as illustrated in Figures 1 and 2 with a part in section and certain parts indicated by broken lines;

2

Figure 4 is a sectional view taken substantially on the line 4—4 of Figure 1;

Figure 5 is a detail sectional view taken substantially on the line 5—5 of Figure 3;

Figure 6 is a detail sectional view taken substantially on the line 6—6 of Figure 4;

Figure 7 is a fragmentary elevational view illustrating a device constructed in accordance with a slightly modified form of invention; and

Figure 8 is a view in top plan with portions broken away of the structure as illustrated in Figure 7.

As illustrated in the accompanying drawings, C denotes a conventional well casing provided at its top with a head H including an outstanding surrounding flange of desired dimensions. This casing C extends the usual distance above the derrick floor (not shown) and extending within the casing C is the usual tubing or line T which, as is well known, is sectional whereby, upon individual handling of the sections, the tubing or line may be readily lowered or withdrawn from the well or bore.

The hanger bracket device, as particularly illustrated in Figures 1 to 6, inclusive, comprises an elongated flat arm 2 provided at one end portion with an arcuate extension 3 adapted to be placed upon a marginal portion of the flange H and removably held thereto by the conventional clamping bolts 4 disposed through the arcuate slots 5 in the extension 3 and through the flange H. These slots 5 permit the arm 2 to be adjusted as may be desired within the limitations of the slots 5 in a manner which is believed to be apparent.

As is clearly illustrated in Figures 3 and 4 of the drawings, the arm 2 which is straight is disposed on such an angle with respect to the extension 3 to permit the arm 2 to be positioned substantially to one side of the radial center of the casing C when the device is applied but with the outer or free extremity of the arm 2 in such radial plane.

The outer or free end portion of the arm 2 rigidly carries an upstanding sleeve or collar 6 opening through the arm 2 and in which is snugly and slidably received an end portion of an elongated post 7 of desired length. This post is adapted to be longitudinally adjusted through the collar 6 as required and to be maintained in desired adjustment by the holding or binding screw 8 threading through the wall of the collar 6 and having binding engagement with the portion of the post 7 within the collar 6.

Freely but snugly surrounding the post 7 above

the arm 2 is a collar 9 integral with an end portion of an arm 10. This mounting of the arm 10 as afforded by the collar 9 allows the arm 10 to freely swing upon the post 7 and the position of the arm 10 above the arm 2 is determined and maintained by the sliding collar 11 surrounding the post 7 and locked in desired selected position on the post in a conventional manner by the binding or holding screw 12 threading through the collar 9 and having required engagement with the post 7.

Hingedly connected, as at 14, with the outer or free end portion of the arm 10 is an end portion of an elongated arm 15 herein disclosed as of a length materially in excess of the length of the arm 10. It is also to be stated that both of the arms 10 and 15 are rigid.

Bolted or otherwise releasably held, as at 16, to the outer or free end portion of the arm 15 is a plate 17 of desired length which is welded or otherwise rigidly secured to the back plate 18 of an oil saver S or to a suitable part of such other equipment with which the bracket device is to be employed.

The oil saver herein disclosed is of a type similar to the saver disclosed and claimed in my issued Patent No. 2,352,412, granted July 11, 1944 and which patented saver forms no part of the present invention.

The arm 15 is provided at a desired point intermediate its ends with an outstanding hand-hold or grasp 19 to facilitate the desired swinging of the arms 10 and 15 in shifting the saver S or other equipment in accordance with the requirements of practice.

In the embodiment of the invention as illustrated in Figures 7 and 8, the lower or base bar 20 is formed at its outer extremity with a collar 21 through which the post 22 is slidably engaged and said collar 21 carries a binding or holding screw 23 for maintaining the post 22 in selected endwise adjustment.

The opposite or inner end portion of the arm 20 is formed to provide a jaw 24 herein disclosed as of a V-type to engage the peripheral portion of the well casing W and coacting with this jaw 24 and opposed thereto for holding engagement with the casing W is a second V-shaped jaw 25. Coacting with the extremities of the jaw 25 and with the arm 20 at opposite sides of the jaw 24 are the tightening members or bolts whereby the base bar 20 is effectively maintained in applied position upon the casing W.

From the foregoing description it is thought to the obvious that a hanger bracket device constructed in accordance with my invention is particularly well adapted for use by reason of the convenience and facility with which it may be assembled and operated.

What is claimed is:

1. In well drilling equipment, means for supporting and centering an oil saver relative to a well casing, comprising an elongated arm, means rigidly securing an end of the same to the upper end of a well casing to extend laterally therefrom, an upstanding post carried by said arm and extending above the upper end of the well casing, a collar slidable on the post, means rigidly locking the collar in selected position upon the post, an arm freely swingably mounted on the post and resting upon the collar, another arm hingedly connected with the second-named arm, and means rigidly securing said last-named arm to an oil saver, the hingedly connected arms being arranged to coact with the first arm to center the oil saver with and above the well casing to which the first arm is secured.

2. In well equipment of the character stated including a well casing and an oil saver unit mounted on said casing and arranged to encase a coupling in a well pipe extending into said casing, the combination with the casing and the oil saver unit of an arm secured to the upper end of the well casing and extending laterally therefrom, a post secured at one end to the arm to extend vertically with respect thereto above and in offset parallel relation with the well casing, a two-part articulated arm, means pivotally coupling the free end of one part of the articulated arm to the post, means rigidly coupling the free end of the other part of the articulated arm with the oil saver unit, means carried by the post for vertical adjustment thereon for supporting the articulated arm at a desired elevation, the articulated arm being of a length relative to the first arm to facilitate centering said oil saver unit with and above the well casing to which the first arm is attached and functioning to permit slight movements of the oil saver and pipe passing therethrough eccentric to the well casing.

WILLIAM J. MILLER.
